UNITED STATES PATENT OFFICE.

FRANZ KISTEMANN, OF NEW YORK, N. Y., ASSIGNOR, BY MESNE ASSIGNMENTS, TO PAPER SERVICE CO., INC., A CORPORATION OF NEW YORK.

DISPENSING-CABINET.

1,254,509.

Specification of Letters Patent. Patented Jan. 22, 1918.

Application filed October 29, 1914. Serial No. 869,200.

To all whom it may concern:

Be it known that I, FRANZ KISTEMANN, a citizen of the United States, residing at New York city, county of Kings, and State of New York, have invented certain new and useful Improvements in Dispensing-Cabinets, fully described and represented in the following specification and the accompanying drawings, forming a part of the same.

10 This invention relates to dispensing cabinets of that class used for delivering interleaved sheets, the especial object being to provide an improved cabinet for use particularly with paper towels, napkins, and the like, although applicable, also, to other uses.

One of the especial objects of the invention is to provide a cabinet which will efficiently deliver paper towels or napkins from a considerable vertical pile, which heretofore has been found difficult, on account of the large weight of the pile upon the sheet being withdrawn, the friction caused by the weight of the pile being such as to interfere with the withdrawal of sheets or even result in the tearing of sheets if of thin material. This difficulty is avoided in accordance with the present invention by providing sheet supports on opposite sides of the delivery which are moved to press against the sheets and relieve the pressure of the pile of sheets upon the portion of a sheet that is being withdrawn. The invention includes providing supports normally forming a flat bottom for the pile of sheets and actuated by the withdrawal of a sheet to raise the stack and present an inclined surface for the withdrawal of the sheet. The supports are preferably mounted so as to rock or tilt, and preferably connected so as to rock in opposite directions as the sheet is withdrawn, the support on the side opposite that from which the sheet is being withdrawn rocking upward at the slot so that it tends to raise the pile of sheets, and the other support rocking downward at the slot so as to present an inclined surface and decrease the angle of delivery and aid in securing an easy withdrawal. The friction of the sheets is preferably further reduced 50 and space for the rolling of the sheet in withdrawal provided, by making the portions of the sheet supports over which the sheets are withdrawn narrow and preferably rounded, so as to further reduce the friction

on the sheet being withdrawn and provide space for the rolling of the sheet in delivery.

In the accompanying drawings forming a part of this specification, there is shown for purpose of illustration a cabinet for interleaved towels or napkins, embodying all the features of the invention in the preferred form now known to me, and certain modifications thereof, and these constructions will now be described in detail and the features forming the invention then specifically pointed out in the claims.

In the drawings:

Figure 1 is an end elevation of the preferred form of cabinet with the end wall broken away to show the construction;

Fig. 2 is a front elevation of the same, partly in section;

Fig. 3 is a detail section, similar to Fig. 1, but on a larger scale and showing the parts in the position of commencing the withdrawal of a sheet;

Fig. 4 is a view similar to Fig. 3, but showing the parts when the operation of withdrawing the same sheet is nearly completed;

Figs. 5 and 6 are views corresponding in position, respectively, to Figs. 1 and 3, showing a modification, and

Fig. 7 is a view similar to Fig. 5, showing another modification.

Referring to the drawings, A is the outer casing of the cabinet, shown as a box adapted to be secured to the wall, as by backing plate B, and having at the front a hinged drop door C by which the box may be filled from the front. The bottom of the box is open or partially open, and at or near the bottom are mounted two plates 10, 11 extending the length of the box and pivoted at 1 in the ends of the box. These plates are separated at their adjacent ends sufficiently to form the usual delivery slot through which the sheets are withdrawn. To secure the rocking or tilting of the plates 10, 11 simultaneously in opposite directions, the plates are provided at opposite ends with arms 12 which are connected by links 13, these arms preferably being inside the box, as shown. The links 13 perform the further function of limiting the tilting of the plates 10, 11 although in some instances this limitation of the tilting movement may be accomplished by other means. Upon the plates 10, 11 are preferably mounted narrow

bars 14, these bars preferably being positioned centrally of the plates, and in line with their pivots, as shown, and extending upwardly so that the sheets rest directly upon them and space is provided between the pile of sheets and the plates 10, 11 outside the bars for the rolling of a sheet in delivery. This feature aids materially in securing the ready and proper delivery of the sheets, although in many cases the plates 10, 11 may be used without these narrow bars. These bars 14 may be rounded on top, as shown, for ease of rocking movement of the plates and withdrawal of the sheets.

25 The operation of the construction will be understood from the drawings and a brief description.

In Figs. 1 and 2 the parts are shown in their normal position, with the plates 10, 11 horizontal, to which position they are returned by the weight of the pile of sheets after the sheet has been withdrawn. On starting the withdrawal of the sheet *x*, the pull on the sheet tilts the plates 10, 11 from the position shown in Fig. 1, to that shown in Fig. 3, the end of plate 10 over which the sheet is being withdrawn being tilted so as to permit the sheet to be withdrawn from an inclined surface and at a less angle than otherwise would be possible, and the adjacent edge of plate 11 being tilted upward at the same time, so that the inner edge of plate 11 lifts the weight of the pile of sheets off the portion of the bottom sheet *x* being withdrawn and thus relieves the friction on this sheet. The friction on the sheet is further reduced by the narrow bar 14, and ample space for the rolling of the sheet outside this bar is provided, as shown in Fig. 4. On the withdrawal of the sheet from the left side of the box, as shown in Fig. 3, the pull of the sheet upon plate 11 rocks the plates 10, 11 in the opposite direction, so that the right hand portion of the sheet is withdrawn over the inner edge of plate 11, and the inner edge of plate 10 acts to lift the pile of sheets and relieve the friction on the sheet being withdrawn until the withdrawal of the sheet is completed. This position of the parts is shown in Fig. 4, in which the sheet started in Fig. 3 is nearly withdrawn and the leading edge of the next sheet has been drawn out for the next delivery. Immediately upon the withdrawal 55 of a sheet the parts are returned automatically by the weight of the pile of sheets from the position shown in Fig. 4 to that shown in Fig. 1.

While I now prefer the construction shown in Figs. 1 to 4 and above described, especially for comparatively large sheets, such as paper towels or napkins, the invention, broadly considered, may be embodied in constructions differing widely from that above described, and, although the rocking

movement of the supports has been found preferable, other movements of the supports may be used under some conditions, so that the rocking movement is not essential to the invention in its broadest aspect. It will be understood, also, that the invention may be applied to other forms of boxes than that shown, and with the sheets withdrawn either alternately from opposite sides of the delivery slot, or always from the same side. While especially applicable to boxes in which the sheets are fed from a vertical pile, and the pile is raised or pressed vertically to relieve the pressure on the bottom sheet, the invention may be applied, also, to constructions in which the sheets lie on their edges, and the pile moves horizontally or in a direction inclined to the vertical under spring or other pressure.

I have shown in Figs. 5 to 7 two modified forms of construction, by which fairly satisfactory results may be secured with certain sheets. In the construction shown in Figs. 5 and 6, rocking supports are used consisting of rolls 15 carried in bars 16 pivoted at 2 centrally and in line with the roll pivots, so that on the withdrawal of a sheet *x*, one roll is lowered and the other raised, as shown clearly in Fig. 6, and on the further withdrawal of the sheet, the bars 16 are rocked 95 in the opposite direction, so as to reverse the rolls, and on the complete delivery of the sheet, the bars and rolls return to their normal position, shown in Fig. 5, the alternate lifting of the pile of sheets at opposite 100 sides of the delivery slot to relieve the pressure on the sheet being withdrawn, being generally the same as that described above in connection with Figs. 1 to 4. In Fig. 7 I have shown a construction similar to that 105 shown in Figs. 5 and 6, except that the pivots 2 of the bars 16 are considerably below the center of the rolls 15, the rocking movement of the rolls thus being somewhat modified. In both of the constructions just 110 described, stops 3 are preferably provided to limit the movement of the bars 16 in opposite directions. Rigid bars may be used in place of the rolls 15, but the rolls are preferable for reducing friction and securing an 115 easy delivery.

It will be understood that the invention is not to be limited to the specific constructions shown and described, as many changes may be made without departing from the scope 120 of the invention as covered by the claims.

What I claim is:

1. A dispensing cabinet having a delivery side with a delivery slot, and means actuated to rise and to press against the pile of sheets 125 on the side of the delivery slot opposite that from which the sheet is being withdrawn and relieve the pressure upon the sheet during withdrawal.

2. A dispensing cabinet having a delivery 130

- side with a delivery slot, sheet supports on opposite sides of the slot, and means for raising said supports to press against the pile of sheets on the side of the delivery slot 5 opposite that from which the sheet is being withdrawn and relieve the pressure upon the sheet during withdrawal.
3. A dispensing cabinet having a delivery side with a delivery slot and sheet supports on opposite sides of the slot, and means for moving said sheet supports in opposite directions by the withdrawal of a sheet, the support over which the sheet is being withdrawn moving away from the pile of sheets 10 and the other support moving toward the pile of sheets to relieve the pressure on the sheet being withdrawn.
4. A dispensing cabinet having a delivery side with a delivery slot, rocking sheet supports on opposite sides of the slot, and means for rocking said supports to press against the pile of sheets on the side of the delivery slot opposite that from which the sheet is being withdrawn and relieve the pressure upon the sheet during withdrawal.
5. A dispensing cabinet having a delivery side with a delivery slot and rocking sheet supports on opposite sides of the slot, said supports being connected to rock in opposite directions during the withdrawal of a sheet, the support over which the sheet is being withdrawn rocking away from the pile of sheets and the other support rocking toward the pile of sheets.
6. A dispensing cabinet having a delivery side with a delivery slot and rocking sheet supporting plates on opposite sides of the slot, said plates being connected to rock in opposite directions during the withdrawal of a sheet, the edge of the plate over which the sheet is being withdrawn rocking away from the pile of sheets and the adjacent edge of the other plate rocking toward the pile of sheets, and single narrow supports carried by the plates and on which the sheets lie, to reduce friction on the sheets and provide space for rolling of the sheet in delivery.
7. A dispensing cabinet having a delivery side with a delivery slot and rocking sheet supporting plates on opposite sides of the slot, said plates being connected to rock in opposite directions during the withdrawal of a sheet, the edge of the plate over which the sheet is being withdrawn rocking away from the pile of sheets and the adjacent edge of the other plate rocking toward the pile of sheets, and narrow bars carried by the plates in line with the plate pivots and on which the sheets lie, to reduce friction on the sheets and provide space for rolling of the sheet in delivery.
8. A dispensing cabinet, having a bottom formed of plates 10, 11, separated to form the delivery slot and pivoted to rock vertically, 15 said plates being linked together to rock simultaneously in opposite directions, substantially as described.
9. A dispensing cabinet, having a bottom formed of plates 10, 11, separated to form the delivery slot and pivoted to rock vertically, 20 said plates being linked together to rock simultaneously in opposite directions, and bars 14 extending upwardly from said plates, substantially as described.
10. A dispensing cabinet, having a bottom formed of plates 10, 11, separated to form the delivery slot and pivoted centrally to rock vertically, said plates being linked together to rock simultaneously in opposite directions, 25 and bars 14 extending upward from said plates in line with the pivots, substantially as described.
11. A dispensing container for interfolded paper comprising a casing having end walls 30 and a hinged front wall, a pair of tilting plates pivotally mounted in said end walls and forming a slot between adjacent edges so that the paper is withdrawn from an inclined surface.
12. In a paper sheet dispensing container having a bottom slot, a pair of tiltable paper sheet supports located on opposite sides of the slot and adapted to move the ends of the paper sheets so as to successively dispose 35 said ends to cause the latter to incline downwardly toward the slot.
13. In a paper sheet dispensing container having a bottom slot, means for raising first one and then the other end of the sheet so as to present and hold the sheet ends in inclined relation to said slot and on opposite sides of the slot during withdrawal.
14. A dispensing cabinet for paper sheets having a slot in the bottom thereof, and a pair of plates located on opposite sides of the slot and mounted so that upon withdrawal of a sheet the latter will actuate the plates to cause the same to raise and incline the sheets toward the slot.
15. A dispensing cabinet having side and end walls, tilting plates pivotally mounted in said end walls, and means for limiting the tilting movement of said plates.
16. A dispensing cabinet for interfolded paper having a hinged front wall and fixed end walls, tilting plates pivotally mounted in said end walls and normally forming a flat bottom for said cabinet, said plates being adapted to assume an angle when the paper is withdrawn, and means for limiting the angle assumed by said plates.
17. A dispensing cabinet for paper sheets having a slot in its bottom, and means having pivotal relation to said bottom, and adapted to support an end of said sheets, said means extending downwardly upon the withdrawal of a sheet and also raising the sheets to cause the same to incline toward the slot.
18. In a dispensing cabinet for stacks of

paper sheets having a bottom slot, a movable paper support mounted so that when a sheet is withdrawn the latter will move one end of the support down and raise the other support end to thereby raise the stack.

19. A dispensing cabinet having a bottom formed of plates 10, 11, separated to form the delivery slot and pivoted to rock vertically, substantially as described.

20. A dispensing cabinet having a bottom formed of plates 10, 11, separated to form the delivery slot and pivoted to rock vertically, and bars 14 extending upwardly from said plates, substantially as described.

21. A dispensing cabinet having a bottom ¹⁵ formed of plates 10, 11, separated to form the delivery slot and pivoted centrally to rock vertically, and bars 14 extending upwardly from said plates in line with the pivots, substantially as described.

In testimony whereof, I have hereunto set my hand, in the presence of two subscribing witnesses.

FRANZ KISTEMANN.
